COMBINED STABILIZER AND ANCHOR CORD
HOLDER FOR DUCK DECOYS

Frank Higgins, Princeton, Ill.

Application February 9, 1944, Serial No. 521,694

3 Claims.

(CL. 43—3).

My invention relates to improvements in combination stabilizers and anchor cord holders for decoy ducks and the like, the principal object in view being to provide a simply constructed, strong, easily applied device acting as a counterweight to stabilize the decoy in the water, or as a rest for maintaining the decoy upright on ice or ground, and which is adapted for easy attachment of an anchor cord thereto when an anchor is used, or for wrapping of said cord around the same when not in use, so that the cord is not visible to game being decoyed.

Other and subordinate objects are also comprehended by my invention, all of which, together with the precise nature of my improvements, will be readily understood when the succeeding description and claims are read with the drawings accompanying and forming part of this specification.

In said drawings:

Figure 1 is a view in side elevation of my improved stabilizer and anchor cord holder applied and illustrating the manner in which the anchor cord is attached when the anchor is in use,

Figure 2 is a fragmentary view in bottom plan drawn to an enlarged scale,

Figure 3 is a fragmentary view in side elevation illustrating the manner in which the anchor cord is wrapped or wound on the stabilizer when the anchor is not in use, and

Figure 4 is a fragmentary view in transverse section taken on the line 4—4 of Figure 2.

Referring to the drawings by numerals, the basic element of my improved stabilizer and anchor cord holder is a substantially diamond-shaped frame 1 provided with a pair of front and rear straight extensions 2, 3. The frame 1 and the extensions 2, 3 are formed of a single, continuous piece of rod-like metal, such as a wire hoop, bent upon itself, said extensions each comprising double lengths of the material engaged side by side and disposed in a common plane with the frame 1 at opposite corners thereof. The extensions 2, 3 are extended through lower barrel-like end keepers 4, 5 on a pair of front and rear T-shaped brackets 6, 7 secured to the bottom of the decoy duck 8 by screws 9 and spaced apart longitudinally of the decoy 8 in the median plane thereof with said keepers 4, 5 depending well below the bottom of the decoy and disposed endwise longitudinally of said decoy. As best shown in Figure 4, the keepers 4, 5 are substantially oval in cross section and arranged with their longer axes transversely of the decoy and the extensions 2, 3 are fitted tightly in said

keepers so that the frame 1 is maintained in a horizontally disposed position when the decoy is in use. As best shown in Figure 2, the frame 1 is fitted between the keepers 4, 5 against end play therebetween and the extensions 2, 3 project forwardly and rearwardly of the keepers 4, 5. The purpose of the projecting ends of the extensions 2, 3 will present appear. The brackets 6, 7 may be inexpensively constructed of a single piece of strap metal bent upon itself, as shown in Figure 4.

The anchor cord 10 is looped around the stem of the front bracket 6 and under the projecting end of the front extension 2 and tied, as best shown in Figure 2 at 11 and may be adjusted to the desired length when the anchor 12 is in use by securing the intermediate portion of the cord to the projecting end of the front extension 2 with a half hitch formed in the cord at a point 20 depending upon the length of anchor cord to be used.

When the anchor 12 and cord 10 are in use, as when the decoy is anchored in the water, the frame 1, extensions 2, 3 and the brackets 4, 5 all act as counterweights to maintain the decoy upright in the water. When the decoy 8 is used on ice or ground, or stored, the anchor cord 10 is wrapped around the stems of the brackets 6, 7 between the decoy and the frame 1 and extensions 2, as best shown in Figure 3, and the anchor is suspended from within the frame 1. When the anchor cord is thus wrapped, the frame 1 and the projecting end portions of the extensions 2, 3 serve to form with the brackets 6, 7 a cleat-like structure on which the wrapped anchor cord is securely confined against displacement therefrom and said anchor cord is hidden from the view of ducks, or other fowl, being decoyed, by the body of the decoy when the latter is used either on ice or upon the ground.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the invention as claimed.

What I claim is:

50. 1. A combined stabilizer and anchor cord holder for a decoy duck comprising a pair of front and rear brackets adapted to be secured to the bottom of said decoy to depend therefrom and including a pair of front and rear lower end keepers of barrel form aligned in the longi-

tudinal center of the decoy, and a rod-like frame of substantially diamond form interposed between said keepers to lie in a plane parallel with the horizontal plane of the decoy and provided with a pair of extensions at opposite corners thereof fitted in said keepers, respectively, and extending forwardly and rearwardly out of the same, respectively, said brackets, frame and extensions forming a cleat-like counterweight structure for maintaining the decoy upright in water, and functioning as a stand for maintaining the decoy upright on ice or land, and an anchor cord secured at one end to the front bracket for wrapping when not in use around said brackets between the decoy and said frame and extensions.

2. A combined stabilizer and anchor cord holder for a decoy duck comprising a pair of front and rear brackets adapted to be secured to the bottom of said decoy to depend therefrom and including a pair of front and rear lower end keepers of barrel form aligned in the longitudinal center of the decoy, and a rod-like frame of substantially diamond form interposed between said keepers to lie in a plane parallel with the horizontal plane of the decoy and provided with a pair of extensions at opposite corners thereof fitted in said keepers, respectively, and extending forwardly and rearwardly out of the same, respectively, said brackets, frame and extensions forming a cleat-like counterweight structure for maintaining the decoy upright in water, and functioning as a stand for maintaining the decoy upright on ice or land, and an anchor cord secured at

one end to the front bracket for wrapping when not in use around said brackets between the decoy and said frame and extensions, said frame and extensions being formed of a single piece of rod-like metal bent upon itself, said keepers being oval in cross section and said extensions comprising double parallel lengths of the rod-like material fitted in said keepers to maintain the extensions and frame stationary relative to the decoy.

- 5 10 3. A combined stabilizer and anchor cord holder for a decoy duck comprising a pair of front and rear brackets adapted to be secured to the bottom of said decoy to depend therefrom and including a pair of front and rear lower end keepers of barrel form aligned in the longitudinal center of the decoy, and a rod-like frame of substantially diamond form interposed between said keepers to lie in a plane parallel with the horizontal plane of the decoy and provided with a pair of extensions at opposite corners thereof fitted in said keepers, respectively, and extending forwardly and rearwardly out of the same, respectively, said brackets, frame and extensions forming a cleat-like counterweight structure for maintaining the decoy upright in water, and functioning as a stand for maintaining the decoy upright on ice or land, and an anchor cord secured at one end to the front bracket for wrapping when not in use around said brackets between the decoy and said frame and extensions, said frame being fitted between said keepers against displacement longitudinally of said decoy.
